UNITED STATES PATENT OFFICE.

JAKE M. STIVERS, OF OKLAHOMA, OKLAHOMA, ASSIGNOR TO THE STIVERS AUTOMATIC COVER COMPANY, A CORPORATION OF COLORADO.

LOCK FOR POOL AND BILLIARD TABLES.

964,581.

Specification of Letters Patent. Patented July 19, 1910.

Application filed January 5, 1907. Serial No. 350,973.

To all whom it may concern:

Be it known that I, JAKE M. STIVERS, a citizen of the United States, residing at Oklahoma city, in the county of Oklahoma, 5 have invented certain new and useful Improvements in Locks for Pool and Billiard Tables, of which the following is a specification.

This invention relates to devices for locking pool and billiard tables against unauthorized use, and pertains particularly to mechanism which is electrically controlled to unlock and lock and remove the obstructions which prevent the use of the tables for 15 the progress of a game.

The object of the invention is to provide a reliable and effective device or apparatus of this character, which will insure the full financial returns to the proprietor from each 20 table and will relieve him of the constant inspection of the tables during hours when the tables are ready for play. I attain these objects by the mechanism illustrated in the accompanying drawings forming a part of 25 this specification, in which—

Figure 1 is a perspective view of a pool table equipped with my locking device and showing the unlocked position; Fig. 2 is a view in perspective of a billiard table provided with my locking device as in its 30 unlocked position; Fig. 3 is a cross section on line x Fig. 1; Fig. 4 is a cross section on line x' Fig. 2; Fig. 5 is a perspective view of the upper portion of the table locking device; 35 Fig. 6 is a longitudinal elevation partly sectional of the solenoid shown in Fig. 5; Fig. 7 is a plan view of the stirrup latch which holds the locking device in an unlocked position.

Similar letters and numerals refer to similar parts in the several views.

Referring to the drawings, Fig. 1 represents a pool table provided with one of my locking devices; A being the table, B the 45 legs, C the pockets, a the major solenoid, b its tubular support containing the spiral spring b' used to lift the solenoid core and the cross-bar c carrying the side-bars c' having secured thereon the vertical ball-rods d 50 bearing the balls d' ; e e' are the duplicate pneumatic checks or brakes connected to piston-rods e' e'' to retard the movement of the solenoid core; e''' is the base upon which are secured the pneumatic checks and the major

solenoid support; f and f' are the electrical 55 solenoid connecting wires.

Referring to Fig. 5, secured within the major solenoid a is the vertical solenoid core tube and guide a'' having duplicate slots in its opposite sides adapted to the vertical 60 movement of the cross-bar c which is prevented from escape by the bolt a''' . Near the top and upon the side of the said guide a'' is secured the laterally projecting stirrup g , supporting the minor solenoid h having 65 secured therein and projecting longitudinally therefrom the solenoid core case or tube h' ; the core i is prevented from escape by the pin i' against which the core i is normally forced by the spiral spring i'' . A 70 cavity or space is thus provided between the inner end of the core and the sliding plunger bar j , the outer end of the latter being loosely secured in the upper end of the locking-bar k , which is pivoted in the saddle k' 75 secured firmly to the semi-casing k'' . The lower end of the said locking-bar is loosely secured in the saddle m firmly secured to the stirrup latch n , its ends being supported by the duplicate guides n' . The adjusting screw 80 m' is for the purpose of regulating the degree of catch of the points of the stirrup-latch over the cross-bar c during the unlocked position as shown in Fig. 5.

When suitable starting mechanism, (not 85 shown) is actuated, the major solenoid becomes energized by current from the wires f and f' , and draws the core a' downwardly. This causes the bar c , with the attached members c' carrying the balls d' likewise to 90 descend, the latter clearing the pockets of the pool table, and thus preparing the pool table for a game. (See Figs. 1 and 3.) The bar c is maintained in its lowered position by the latch n , which is controlled by the 95 minor solenoid h , the latter being suitably energized in conjunction with the starting mechanism to unlock the bar c at the end of a predetermined time. Thus, at the end of such a period, the solenoid h is energized to 100 cause the core i to strike the plunger j which in turn, trips the latch n to withdraw the latter from engagement with bar c . When released, said bar is forced upwardly by the action of springs b' on the core a' and the 105 balls d' again enter the pockets to lock the table against use.

Figs. 2 and 4 show a modified form of my

invention as applied to billiard tables, in which the ends of the cross-bar *c* are bent upward and attached to the side bars which are shorter and also the ball standards or 5 supporting rods *d* to the upper ends of which the balls *d'* are loosely attached and have elbow-like arms 1 pivoted to the sides of the table A in a manner to project the game-blocking rods 2 from their hiding place under 10 the table railing, the dotted lines showing the locked or blocked position.

Having thus described my invention, what I claim as new and useful and desire to secure by Letters Patent, is—

- 15 1. In a game table, the combination with the pockets of a plurality of balls mounted to enter said pockets, means for supporting said balls for vertical reciprocative movement, and means for actuating said supporting means to simultaneously remove from or enter said balls in said pockets.
- 20 2. In a game table, the combination of a major solenoid mounted below said table, a vertically movable core mounted in said 25 solenoid, bars and cross-bars mounted on and actuated by said core, and means carried by said crossbars mounted to engage said game-table to block the playing of games thereon.
- 25 3. In a game-table, the combination of a

series of pocket closing balls, ball rods carrying said balls for vertical movement, side bars supporting said ball rods, a cross-bar supporting said side bars, a solenoid below said table, a core movable in said solenoid and mounted to support said cross-bar, a coil spring adapted to maintain said core at its highest point, a latch adapted to lock said core at its lowest point of movement, and a minor solenoid adapted to control said latch to release said bar.

4. In a game table, the combination of a series of pocket-closing balls, ball-rods carrying said balls, side-bars supporting said ball-rods, a cross-bar carrying said side-bars, a solenoid, a core in said solenoid having said cross-bar mounted thereon, and pneumatic checks mounted adjacent said solenoid, piston rods mounted in said checks and secured to said cross-bar, said checks being adapted to regulate the downward movement of said core and its supported elements.

In testimony whereof I affix my signature in presence of two witnesses.

JAKE M. STIVERS.
